OIL APPLYING APPARATUS FOR STRIP MATERIAL

John N. Savastone, Steubenville, Ohio, assignor
to National Steel Corporation, a corporation of
Delaware

Application July 23, 1945, Serial No. 606,655

9 Claims. (Cl. 91—39)

1

This invention relates to apparatus for applying oil to strip and sheet material and the like, and is more particularly concerned with apparatus for applying uniformly the proper amount of oil to longitudinally moving strip, especially while the strip is being wound on a coiling reel.

It is often necessary or desirable to apply a protective coating of oil to metallic strip or sheet material. For example, customers require that black plate, which is usually sold in coils, be coated with oil. A customary practice is to immerse the coils in a bath of oil or pass the strip through a bath of oil. In either procedure, it is difficult, if not impossible, to accurately control the amount of oil applied to the strip. If too much oil is applied, the coils may collapse and if an insufficient quantity of oil is applied, the strip may corrode so that the customer will refuse to accept it and the manufacturer has to scrap the material. Thus, applying the proper amount of oil to strip material such as black plate strip has been difficult and there has been a need for apparatus for applying uniformly the proper amount of oil.

While this invention will be more particularly described in connection with applying oil to strips of black plate while being wound on the reel of a coiler, it is not limited to black plate or to coilers and may be used to apply oil to other materials at other locations.

A primary object of this invention is to provide an improved apparatus for applying the proper amount of oil to strip material and in which the rate of flow and the distribution of oil may be regulated readily and accurately.

Another object of this invention is to provide such an apparatus which may be readily adjusted for applying the proper amount of oil to successive strips of different widths.

A further object of this invention is to provide an apparatus for applying the proper amount of oil to longitudinally moving strip while being coiled on a reel.

A still further object of the present invention is to provide an apparatus which may be used with a strip coiling reel and a coil starting means for applying the proper amount of oil to the strip while being coiled on the reel.

The present invention provides an improved oiling apparatus especially suited for successively

2

applying the proper amount of oil to successive strips of the same and different widths while the strip is being coiled or wound on a reel. The apparatus includes an oil distributing element, means for supplying oil to this element and supporting means constructed and arranged to permit upward and downward movement of the oil distributing element and to normally urge the oiling element downwardly against the strip under the influence of gravity. Means are provided for varying the effective width of the oil distributing element and for controlling the distribution of the oil. A skid is provided for engaging the coil starting mechanism when this mechanism is moved into the operative position adjacent the reel for starting a coil so that the coil distributing element is automatically moved up out of the way and only a minimum amount of strip is not oiled. The unoiled strip must later be removed. This apparatus has been found to function in a highly satisfactory manner.

These and other objects and advantages will become more apparent from the following detailed description and the accompanying drawings, in

which:

Figure 1 is an elevational view with portions removed to more clearly show the internal structure of an apparatus embodying the principles of the present invention; and,

30 Figure 2 is an elevational view with portions in section and taken along line 2—2 of Figure 1.

Referring more particularly to the drawings, the strip material 10, which in this particular instance is black plate, being taken from the final 35 temper rolls of a temper mill, not shown, may be any other strip material such as steel strip, cold rolled steel strip, hot rolled steel strip, tin plate and the like, being taken from the final rolling operation, heat treating operation, or the like. As the black plate 10 is taken from the final temper rolls, it is coiled on power driven, rotating reel 11 into coil 12. When the coil 12 has attained the proper size, it is removed and another coil is started. The reel may be of any one of the well known types such as those available on the market.

The coil starting apparatus 14 includes a frame 15, belt 16 and a belt tensioning device 17. After a coil has been completed and removed from reel 50 11, the coil starting apparatus is moved to the left

to an operative position adjacent reel 11. In this position, the belt 16 extends nearly around the reel 11 and the leading end of the strip can be inserted between the belt and reel and the reel rotated to start a new coil. After the coil is started, the coil starting means 14 is moved toward the right to the inoperative position shown in the drawings.

While this invention is not limited to any particular type of reel and coil starting mechanism, they may be of the general type shown in the United States Patent No. 2,322,784, issued June 29, 1943 to C. J. Klein.

The oil distributing brush 18 includes a wooden back 19 in which are mounted oil spreading bristles 20. The brush 18 extends transversely of strip 10 and is as long as the widest strip to be oiled. The oil is supplied to the brush 18 at spaced points throughout its length by a plurality of separate tubes 21, each extending through the wooden back 19 as shown more clearly in Figure 2. Each oil supply tube is screwed into one side of a pet cock 22 which is connected through a nipple 23 to a corresponding T or elbow pipe connection 24. All of the pipe connections 24 are connected in line by nipples 25 to a T connection 26 so that the oil supplied to connection 26 flows to brush 18 at a plurality of spaced points. The amount of oil flowing through each tube 21 can be regulated by adjusting the corresponding valve 22 or can be shut off when desirable. The T joint 26 is connected through unions 28, elbows 29, elbows 30 and valve 31 and pressure gauge 32 to a T connection 33. The valve 31 can be adjusted to vary the total amount of oil or closed to entirely shut off the flow of oil. The connection 33 is connected to the main oil supply pipe 34 which in turn is connected through elbow 35, pipe 36, swivel connection 37 and pipe 38 to a source of oil. Thus, oil is supplied to the brush 18 at spaced points therealong by a plurality of passage containing members, each associated with a valve for individually controlling and regulating the flow of oil therethrough to vary the effective width of the oil distributing brush 18 and to vary the amount of oil flowing to the brush and to control the distribution of the oil along the brush.

The oil supply pipes and swivel connection 37 also support the brush 18 for movement in an arc downwardly toward and upwardly away from an operative position adjacent strip 10 as it is being longitudinally wound on the reel 11. The brush 18 is normally urged against strip 10 under the influence of gravity and can move upwardly during winding of the coil 12 against the influence of gravity to compensate for the rising level of the strip as the diameter of the coil 12 increases.

A skid 40 is fastened to oil supply pipe 34 in position so that when the coil starting mechanism is moved toward reel 11 to an operative position adjacent the reel for starting a new coil, the upper portion 41 of mechanism 14 strikes the skid 40 and raises brush 18 away from the reel 11 and the strip to an inoperative position against the influence of gravity. After the new coil has been started, the coil starting mechanism is moved away from the reel 11 to an inoperative position and the brush 18 drops down against the strip 10 so that only a very small amount of the starting end of the strip is not oiled. This reduces the amount of scrap.

If the strip to be coiled is narrower or wider than the previous strip, the effective length of

the brush is decreased or increased by closing or opening the end valves 22 and the other valves 22 may be adjusted, if desirable, to control distribution of the oil. Either valves 22 or valve 31 may be adjusted to vary the total amount of oil applied to the new strip. Once valves 22 are adjusted for the proper distribution of the oil, the total flow may be readily adjusted by means of valve 31. Before starting a coil, the coil starting mechanism 14 is moved toward the left until the belt 16 extends nearly around the reel 11. The upper portion 41 of mechanism 14 engages skid 40 and swings the brush 18 up and away from the reel. After the coil starting mechanism is in position, the leading end of the strip is inserted between reel 11 and belt 16 and reel 11 is turned through at least one revolution. The belt 16 causes the strip to wrap around reel 11 to start a new coil 12. The mechanism 14 is then moved out of the way and the brush automatically moves downwardly against the strip. As the reel is rotated to coil the strip, the brush and strip are relatively moved in a direction extending longitudinally of the strip to apply the proper amount of oil along the strip and as the level of the strip rises due to the increasing size of the coil, the brush automatically moves upwardly.

Having described my invention in detail, it is obvious that certain changes can be made therein without departing from the spirit or scope of my invention. For example, the oil supplying means and the supporting means for the brush may be separate and oil distributing elements other than brushes may be used.

I claim:

1. Apparatus for applying the proper amount of oil to a longitudinally extending strip comprising an oil distributing brush extending transversely of the strip; means including a plurality of oil passages for supplying oil to said oil distributing brush at spaced points throughout its length; adjustable valve means associated with said oil supplying means for individually controlling and regulating the flow of oil through each oil passage to said oil distributing brush; support means supporting said oil distributing brush in an operative position adjacent the strip; and means for relatively moving the strip and said oil distributing brush in a direction extending longitudinally of the strip to distribute oil along the strip.

2. Apparatus for applying the proper amount of oil to a longitudinally extending strip comprising an oil distributing brush extending transversely of the strip; means including a plurality of oil passages for supplying oil to said brush at spaced points throughout its length; adjustable valve means associated with said oil supplying means for individually controlling and regulating the flow of oil through each oil passage to said brush; support means supporting said brush for movement toward and away from an operative position adjacent the strip and normally urging said brush against the strip under the influence of gravity; and means for relatively moving the strip and said brush in a direction extending longitudinally of the strip to distribute oil along the strip.

3. Apparatus for applying the proper amount of oil to a longitudinally extending strip comprising a reel for coiling the strip into a coil and for longitudinally moving the strip; an oil distributing brush extending transversely of the strip; means for supplying oil to said brush at spaced points throughout its length; and support means

supporting said oil distributing brush in an operative position adjacent the strip above the coil of strip on said reel to distribute oil over the strip.

4. Apparatus for successively applying the proper amount of oil to successive longitudinally extending strips of the same and different widths comprising an oil distributing brush extending transversely of the strip and having a length equal to the widest strip to be oiled; means including a plurality of oil passages for supplying oil to said oil distributing brush at spaced points throughout its length; adjustable valve means associated with said oil supplying means for individually controlling and regulating the flow of oil through each oil passage to said oil distributing brush to vary the effective width of said oil distributing brush according to the width of the strip and to vary the amount of oil applied to the strip; support means supporting said oil distributing brush in an operative position adjacent the strip; and a reel for longitudinally moving the strip and for coiling the strip into a coil as it is oiled to distribute the oil over the strip, said oil distributing brush being adjacent the strip above the coil.

5. Apparatus for successively applying the proper amount of oil to successive, longitudinally extending strips of the same and different widths and adapted to be used with a strip coiling reel and a coil starting mechanism movable toward and away from an operative position adjacent the reel, said apparatus comprising an oil distributing element extending transversely of the strip; a plurality of passage-containing members spaced along said oil distributing element for supplying oil at spaced points therealong; adjustable valve means associated with each of said members for individually controlling and regulating the flow of oil through each member to said oil distributing element to vary the effective width of said oil distributing element according to the width of the strip and to vary the amount of oil applied to the strip; support means supporting said oil distributing element for movement toward and away from an operative position adjacent the strip and normally urging said element against the strip under the influence of gravity; and a skid operatively connected to said oil distributing element in position to engage the coil starting mechanism only upon its movement to an operative position adjacent the reel to raise said oil distributing element away from the strip against the influence of gravity.

6. Apparatus for successively applying the proper amount of oil to successive, longitudinally extending strips of the same and different widths and adapted to be used with a strip coiling reel and a coil starting mechanism movable toward and away from an operative position adjacent the reel, said apparatus comprising an oil distributing brush extending transversely of the strip and having a length equal to the widest strip to be oiled; a plurality of passage-containing members spaced along said brush for supplying oil at spaced points therealong; adjustable valve means associated with each of said members for controlling and regulating the flow of oil through each of said members to vary the effective width of said brush according to the width of the strip; support means supporting said oil distributing brush for movement downwardly toward and upwardly away from an operative position adjacent the strip and normally urging said brush downwardly against the strip under the influence of gravity; and

gravity; and a skid operatively connected to said brush in position to engage the coil starting means only upon its movement into an operative position adjacent the reel to raise said brush away from the strip to an inoperative position against the influence of gravity and to permit return movement of said brush under the influence of gravity to an operative position adjacent the strip upon movement of the coil starting means away from the reel to an inoperative position.

5. In combination with a strip coiling reel and a coil starting mechanism supported for movement toward and away from an operative position adjacent the reel, apparatus for applying the proper amount of oil to the longitudinally extending strip comprising an oil distributing element extending transversely of the strip; means for supplying oil to said oil distributing element throughout its length; support means supporting said oil distributing element for movement toward and away from an operative position adjacent the strip; and a skid operatively connected to said oil distributing element arranged in position to engage the coil starting mechanism only upon its movement to an operative position adjacent the reel so that movement of the coil starting mechanism to the operative position moves the skid and the oil distributing element to an inoperative position.

10. 8. In combination with a strip coiling reel and a coil starting mechanism movable toward and away from an operative position adjacent the reel, apparatus for applying the proper amount of oil to the longitudinally extending strip comprising an oil distributing element extending transversely of the strip; means including a plurality of oil passages for supplying oil to said oil distributing element at spaced points throughout its length; adjustable valve means associated with said oil supplying means for individually controlling and regulating the flow of oil through each oil passage to said oil distributing element; support means supporting said oil distributing element for movement to an operative position adjacent the strip as it is being coiled on the reel and supporting said oil distributing element for movement away from the operative position to an inoperative position and normally urging said oil distributing element against the strip under the influence of gravity; and a skid operatively connected to said oil distributing element arranged in position to engage the coil starting mechanism only under its movement to the operative position adjacent the reel, said skid being so constructed and arranged that movement of the coil starting mechanism to the operative position adjacent the reel moves the skid and the oil distributing element to the inoperative position against the influence of gravity.

9. Apparatus for applying the proper amount of oil to a longitudinally extending strip comprising a brush extending transversely of the strip and including a back and bristles; a plurality of separate passages spaced along and extending through said brush back for supplying oil at spaced points to the bristles; adjustable valve means associated with each of said passages for individually controlling and regulating the flow of oil through each passage to said brush to vary the effective width of said brush according to the width of the strip and to vary the total amount of oil supplied to the strip; support means supporting said brush for movement toward and away from an operative position adjacent the strip and normally urging the bristles of said brush against the strip under the influence of gravity; and

7
means relatively moving the strip and said brush in a direction extending longitudinally of the strip to distribute oil along the strip.
